(57) CLAIM

The ornamental design for a crossbow case, as shown and described.

DESCRIPTION

FIG. 1 is a perspective view of a crossbow case.
FIG. 2 is a top view of the crossbow case shown in FIG. 1;
and,
FIG. 3 is a right side view of the crossbow case shown in FIG. 1.

The broken line showing is included for the purpose of illustrating unclaimed subject matter and forms no part of the claimed design.

1 Claim, 3 Drawing Sheets

FIG. 1

FIG. 3
